ASSIGNORS TO THE WESTINGHOUSE AIR BRAKE COMPANY, OF WILMERDING, PENN-
SYLVANIA, A CORPORATION OF PENNSYLVANIA.

COMBINED CAR, TRAIN-PIPE, AND ELECTRIC COUPLING.

1,282,777.

Specification of Letters Patent. Patented Oct. 29, 1918.

Original application filed March 24, 1913, Serial No. 756,469. (Now Patent No. 1,316,294, dated February 20, 1917.) Divided and this application filed May 19, 1914. Serial No. 839,507.

To all whom it may concern:

Be it known that we, JAMES S. DOYLE and FRANK HEDLEY, both citizens of the United States, residing, respectively, at Mount Vernon and Yonkers, in the county of Westchester and State of New York, have invented a certain new and useful Improvement 5 in Combined Car, Train-Pipe, and Electric Couplings, of which improvement the following is a specification.

This invention relates to car coupling devices, and also to mechanism for automatically coupling train pipe connections, and electric train line circuits between the cars 15 or other vehicles of a train. One of the features of this present improvement relates more particularly to a car coupling of the so-called rigid lock type in which hook shaped projections having vertical plane surfaces engage each other by a relative lateral 20 movement and are tightly held by pivoted locking levers, and one of the objects is to provide fluid pressure means for actuating the locking levers to release the couplers.

Another feature relates to the train pipe 25 coupling devices which are carried by the car couplers, the object being to provide improved automatic valvular means for controlling the ends of the pipe sections, in order to perform the functions of the usual 30 angle cocks, when the cars are uncoupled or when they are coupled together. Another object is to provide means for preventing the closing of the valves in the train brake pipe 35 connections when the couplers are accidentally pulled apart in order to permit the escape of air and produce an application of the brakes, but at the same time to permit the automatic closing of said valves when 40 they are intentionally uncoupled and separated.

Still another object is to provide a manually operated switch and valve mechanism upon the end of each car, with proper circuit 45 connections to the couplers for controlling the release of the locks of both couplers and for setting up the desired circuit connections for the car control system.

These and other objects will hereinafter 50 more fully appear from the following description of one form of apparatus embody-

ing the various features of our improvement, the novel construction and combinations being set forth in the claims.

This application is a division of our original 55 application Serial No. 756,469, filed March 24, 1913.

In the accompanying drawings: Figure 1 is a horizontal section, taken substantially on the line 1—1 of Fig. 4, and showing two 60 counterpart couplers in the coupled position; Fig. 2, a horizontal section through the hooked portion of the couplers, showing the same locked together; Fig. 3, a side view of the inside or locking face of the 65 coupler; Fig. 4, an outside elevation of one of the couplers complete; Fig. 5, a vertical section of the switch box, and valve for manually controlling the releasing operation of the coupler mechanism; and Fig. 6, a diagram 70 of the electric circuits connected through the coupler to the switch boxes of the adjacent ends of two cars coupled together.

According to the construction shown in 75 the drawings, the coupler comprises a main casting or coupler head, 12, adapted to be secured, preferably by a pivotal connection, 13, to the draw bar (not shown) and having a hook shaped projection, 14, provided with 80 a vertical plane surface, 15, inclined at an angle to the line of draft and adapted to engage and interlock with a corresponding surface on the projection of a counterpart coupler by a relative lateral movement 85 when said couplers come together in the act of coupling. Each coupler is also provided with a movable lock, 16, preferably pivoted as shown, and adapted to bear against a surface, 17, on the outer side of the projection, 90 14, of the counterpart coupler and hold said couplers securely clamped together when in coupled position, the construction as thus far described being similar to that of prior 95 Westinghouse Patent No. 708,747, of September 9, 1902.

According to one of the features of our present improvement, fluid pressure means are provided for releasing the lock of the coupler, a preferred construction for this 100 purpose comprising a cylindrical chamber formed in the coupler head and containing

a piston, 18, which is connected by a rod, 19, with an arm of the pivoted lock, 16, a spring, 20, acting on the back of the piston to normally hold the same and the pivoted lock 5 in its locking position. Fluid under pressure, such as compressed air, may be admitted from a pipe connection, 21, through passage, 22, and port, 23, to the face of piston, 18, to move the same outward against 10 the spring, 20, and actuate the pivoted lock, 16, to its releasing position, as indicated in dotted lines in Fig. 1. Any suitable valve means may be employed for controlling the supply and release of the fluid to and from 15 the cylinder.

For the purpose of establishing a connection for the train pipe lines through the coupling, one or more passages, 24, communicating with respective pipe connections, 40, may be provided through the coupler head, preferably near the center of the coupling faces, and each having a gasket, 25, mounted in the open end of said passage substantially at right angles to the vertical 25 plane, 15, and adapted to squarely engage the corresponding gasket of the counterpart coupler as the two parts come together in line with the plane, 15. The passages are also provided with valves, 26, for opening 30 and closing said passages automatically, as the couplers come together and separate, said valves having springs, 27, normally tending to seat the same, and stems, 28, extending in line with or parallel with the 35 plane, 15, and projecting through the gasket opening for engaging the corresponding stems of the counterpart coupler when the same are brought together. Flexible pipe or hose may be attached to the respective 40 pipe connections, 40, and 21, in order to provide for the movement of the couplers.

While it is desirable that the valves should close automatically, and prevent the escape of fluid when the couplers are intentionally released and separated, it is also important, in the case of the train brake pipe, that it should remain open and vent to the atmosphere in order to effect an automatic application of the brakes if the 45 couplers should accidentally be pulled apart as when there is a break-in-two of the train, and in order to provide for this contingency, a small detent, 29, attached to piston, 30, is mounted in a chamber at the side of the 50 valve, 26, and is normally held outward by a spring, 31, to prevent the valve, 26, from closing should the couplers be accidentally pulled apart. In order that the detent may be automatically withdrawn when it is desired 55 to release the couplers and separate the cars, the piston, 30, is normally balanced as to the train pipe pressure in passage, 24, by the leakage thereof around or through a small port to the space at the back of the 60 piston, from which space a port, 32, com-

municates with the chamber, 33, of vent valve, 34, actuated by the piston, 35, subject to the fluid pressure admitted to pipe, 21, and passage, 22.

When the two counterpart couplers come 70 together in the act of coupling, the projections, 14, are guided into the corresponding recesses by the inclined surfaces, and there is a relative lateral movement of the couplers sufficient to permit the hook shaped 75 projections to clear each other as they enter the corresponding recesses where they engage and force back the respective locks, 16, against the springs, 20, of the counterpart coupler heads. The projections then move 80 inward and laterally along the engaging surface, 15, to the closed or coupled position in which the locks, 16, spring outward and engage the respective surfaces, 17, of the 85 coupler projections and clamp the same together tightly. During this movement along the surfaces, 15, the projecting stems, 28 of the valves, 26, engage each other in the line of this movement and force said valves, 26, back off their seats to their open positions, 90 at the same time that the gaskets, 25, seat squarely together forming a fluid tight joint, and opening free communication between the respective sections of train pipe lines 95 on the adjacent cars. In the passage of the train brake pipe connection, the detent, 29, is held out beneath the valve, 26, and the fluid pressure of the train pipe equalizes around the piston, 30, and throughout the port, 32, to the vent valve, 34, which is closed. 100

When it is desired to release the couplers and separate the cars, fluid under pressure is admitted through pipe, 21, and passage, 22, where it acts on the piston, 35, opening the vent valve, 34, and the port, 23, leading 105 into the cylinder of piston, 18, which is forced outward against the spring, 20, and releases the lock by withdrawing the same to its retracted position. At the same time, the fluid from the back of piston, 30, is 110 vented to the atmosphere through port, 32, valve, 34, and port, 36, whereupon the train pipe pressure forces the piston, 30, and the detent, 29, back to its retracted position and the couplers are free to be pulled apart. As 115 the couplers separate, the projections slide laterally upon the engaging surfaces, 15, and the valves, 26, are automatically closed upon their seats by the springs, 27, thereby preventing the escape of fluid from the train pipe lines. The fluid pressure may then be released from the pipes, 21, and passage, 22, whereupon the vent valve, 34, is closed and the piston, 18, and lock, 16, are returned to the normal locking position ready for being again coupled with another car. If the couplers should be accidentally pulled apart at any time, the detent, 29, prevents the closing of the valve, 26, in the train brake pipe 125 connections, whereby the compressed air 130

will be vented to the atmosphere and cause the desired application of the automatic brakes upon the train.

While various forms of valve devices for controlling the supply of fluid to, and its release from, the pipe, 21, for releasing the couplers, may be used, we prefer to employ a device of the character shown in Figs. 5 and 6, and this feature of our improvement 10 comprises valve means, such as admission valve, 50, for supplying fluid from a suitable source, represented by pipe, 51, to the pipe, 21, and an exhaust valve, 52, for controlling the release from pipe, 21, to the atmosphere, the valves being arranged in line with each other, and having abutting stems so that one valve opens as the other closes, and both being operated by a stem, 53, attached to the core, 54, of the electromagnet 20 or solenoid coil, 55. A spring, 56, normally holds the admission valve, 50, closed, and the exhaust valve, 52, open when the solenoid is deenergized. For controlling the action of the solenoid we provide a switch box, 57, containing a switch lever, 58, having a handle, 59, and electrically connected at 60, to one end of the magnet coil, 55, while the other end of the coil may be connected by a lead, 61, through an electric coupling 25 between the cars, with the corresponding end of the magnet coil of the counterpart device on the adjacent car, as indicated in the diagram, Fig. 6. The switch box also has a contact, 62, connected by lead, 63, with a 30 source of current supply, such as a positive tap from the car control resistance, 64, and another contact, 65, with a lead, 66, to a ground or a negative wire connection through the coupling to the adjacent car. The core 35 of the magnet or solenoid is also connected by a rod, 67, with a pivoted arm, 68, having a notch or detent, 69, for holding the end of the switch lever, 58, when the same is turned to its vertical position, engaging the contact, 62, for releasing the locks of the 40 couplers. A spring, 70, normally holds the switch lever, 58, in its inactive position, as shown in the drawings, in which the couplers are locked together, or in which the 45 locks are in position for coupling.

When it is desired to release the locks of the couplers, the switch lever, 58, on one of the cars, is thrown to its vertical position, in which it engages contact, 62, thereby energizing the coils, 55, of the solenoids upon the adjacent ends of both cars by current through wires, 63, 60, 61, on the one car, and through the coupling and wires, 61, 60, switch bar, 58, contact, 65, and lead, 66, on 50 the other car. Both solenoids then operate to close exhaust valves, 52, and open the admission valves, 50, against the springs, 56, and the fluid pressure beneath the valves, thereby supplying fluid pressure to the 55 pipes, 21, and releasing the locks, 16, of both

couplers as before described. At the same time, the pivoted arm, 68, is drawn down by the core, 54, of the solenoid and the detent or notch, 69, holds the switch lever in said position until the solenoid is deenergized. When the couplers are then separated by pulling one car away from the other, the circuit, 61, is broken and the coils, 55, are therefore deenergized, whereupon the spring, 56, operates to close valve, 50, open 70 exhaust valve, 52, and raise the solenoid, and the detent arm, 68, to free the switch arm, 58. The spring, 70, then returns the switch arm to its normal position in which it engages the contact, 65. It will therefore 80 be seen that it is only necessary for the operator to set the switch lever to the unlocking position, and give it no further attention, as it will be automatically returned to its normal position as soon as the cars are 85 separated.

In order that the control circuits on the car on which the switch lever is set for releasing the couplers may be in proper condition for controlling the car to propel the 90 same, while the control circuit on the adjacent car is temporarily interrupted, we may provide two additional contacts, 71 and 72, in the switch box, said contacts being connected by a spring bar, 73, operated by the 95 movement of the switch lever to its normal position, and disconnected when the lever is moved to its releasing position. One of these contacts is connected by lead, 74, with one terminal of the line switch, coil, S, while 100 the other contact, 72, is connected by lead, 75, through the coupling with the corresponding contact of the counterpart switch box at the proximate end of the adjacent car. As the other terminals of the line switches 105 upon the respective cars are connected by a train line circuit, 76, it will be seen that when one of the switch levers is set for releasing the couplers, the control circuit through the line switch of that same car will 110 be alive and in condition to control the propelling motors to move that car away from the adjacent car on which the circuit to the line switch is interrupted by the opening of the same at contacts, 71 and 72, of the switch 115 that was thrown. As soon as the cars are separated, either car may be controlled in the usual manner.

It will now be apparent from the foregoing description, that we have provided 120 an improved and efficient coupling apparatus by means of which the draft connections, and the fluid pressure train pipe lines are automatically coupled and uncoupled whenever a car is added to or detached from the train 125 or another car, the only attention necessary on the part of the motorman or operator being to throw the release switch handle when he wishes to detach one of the cars.

Having now described our invention, what 130

we claim as new and desire to secure by Letters Patent is:

1. In a car coupling, the combination with a coupler head, a movable lock, and a piston for releasing said lock, the locks of two counterpart couplers of adjacent cars being adapted to hold said couplers clamped together, a magnet valve device on each car for controlling the pressure acting on the piston, a circuit extending between the cars and connecting said magnets, and a switch device on each car for controlling said circuit.
2. In a car coupling, the combination with a coupler head, a movable lock, and a piston for releasing said locks, the locks of two counterpart couplers of adjacent cars being adapted to hold said couplers clamped together, a magnet valve device on each car for controlling the pressure acting on the piston, a circuit extending between the cars and connecting said magnets, a switch on each car for controlling said circuit and having means for normally holding said switch in

locking position, and a detent governed by the magnet coil for temporarily holding said switch in releasing position.

3. In a car coupling, the combination with a coupler head, a movable lock, and a piston for releasing said locks, the locks of two counterpart couplers of adjacent cars being adapted to hold said couplers clamped together, a magnet valve device on each car for controlling the pressure acting on the piston, a circuit extending between the cars and connecting said magnets, car control circuits also extending between the cars, and a switch device on each car and having contacts for controlling both the magnet valve circuit and the car control circuit.

New York, New York. May 18, 1914.

JAMES S. DOYLE.
FRANK HEDLEY.

Signed in the presence of—
WARREN MARCUS,
CHARLES V SMITH.

It is hereby certified that in Letters Patent No. 1,282,777, granted October 29, 1918, upon the application of James S. Doyle, of Mount Vernon, and Frank Hedley, of Yonkers, New York, for an improvement in "Combined Car, Train-Pipe, and Electric Couplings," the grant shows the patent to be issued to the inventors said Doyle and Hedley, whereas it should be stated after line 5, *They having assigned their right, title, and interest to The Westinghouse Air Brake Company, of Wilmerding, Pennsylvania, a corporation of Pennsylvania;* strike out present line 13 and insert *The Westinghouse Air Brake Company, its successors or assigns;* and that the said Letters Patent should be read with this correction therein that the same may conform to the record of the case in the Patent Office.

Signed and sealed this 22d day of April, A. D., 1919.

[SEAL.]

F. W. H. CLAY,

Acting Commissioner of Patents.
